UNITED STATES PATENT OFFICE

1,975,898

ELECTRICAL CONTROL SYSTEM

Lawrence A. Hyland, Washington, D. C., assignor
to Wired Radio, Inc., New York, N. Y., a corpora-
tion of Delaware

Application May 6, 1929, Serial No. 369,905

2 Claims. (Cl. 250—20)

My invention relates broadly to circuit ar-
rangements for electron discharge devices, and
more specifically to electron discharge devices
employed for controlling the resistance of cir-
cuits.

One of the objects of my invention is to pro-
vide a variable resistor employing an electron
discharge device in which the variable resistance
circuit is electrically isolated from other circuits
associated with the electron discharge device.

Another object of my invention is to provide
a variable resistance apparatus employing an
electron discharge device having an electron
emitting electrode, an anode and a heating elec-
trode, in which the circuit of the heating elec-
trode is isolated from the circuits of the electron
emitting electrode and the anode.

Still another object of my invention is to pro-
vide a variable resistor employing an electron
discharge device for controlling the operation of
circuits of other electron discharge devices.

A further object of my invention is to provide
a variable resistor employing an electron dis-
charge device for controlling the operation of cir-
cuits of other electron discharge devices in which
all of the electron discharge devices employ or
are adapted to employ the same source of cathode
energization supply.

My invention will be more fully understood
from the specification hereinafter following by
reference to the accompanying drawings.

According to my invention an electron dis-
charge device having an anode, a cathode and a
heating electrode which is electrically insulated
from the cathode but thermally associated there-
with, is employed as a continuously variable re-
sistor. The resistance of the path between the
electron emitting electrode and the anode is va-
ried by varying the heating current flowing
through the heater electrode. Since the heater
electrode is electrically isolated from the cathode
the same source of heating current may be em-
ployed for energizing the cathode which is oper-
atively associated with other circuits which may
be at a different potential. For example, where
the resistor of my invention is employed to control
the resistance of the grid circuit of electron dis-
charge devices, the same source of current may
be used to energize the cathodes of the resistor
and the electron discharge device. Likewise the
electron discharge resistor of my invention may
be employed to control the anode current of
electron discharge device amplifier and oscilla-
tion generator arrangements in cases where the
same source of current supply is employed in

energizing the cathode of the resistor as well as
the cathodes of the other electron discharge de-
vices.

In the drawings, Figure 1 illustrates schemati-
cally the variable resistor of this invention; 60
Fig. 2 also is a schematic illustration of the vari-
able resistor of this invention; and Figs. 3 and 4
are circuit arrangements incorporating the re-
sistor of this invention.

Reference numeral 1 of Fig. 1 of the drawings 65
designates an electron discharge device having
an anode 2, a heater electrode 4 and an electron
emitting electrode 3, which is energized thermally
through the action of the heat transmitted to
it from the heater electrode 4. The electrode 3 70
and the heater electrode 4 are electrically isolated
from each other. The heater electrode 4 may
be surrounded by an insulating member of mica,
quartz or similar material, the electrical insulat-
ing properties of which do not materially de- 75
teriorate as the temperature of the member is
increased and the electron emitting electrode 3
may be mounted upon the exterior of the insu-
lating member in order to receive heat from the
heater electrode by conduction or the electrode 80
3 may be supported in the vacuous space within
the electron discharge device 1 adjacent to the
heater electrode 4. A source 5 of heating cur-
rent is connected to the variable resistance unit
6 and the electrode 4. 85

In Fig. 2 is illustrated a modified form of the
invention in which the electron discharge device
7 which is provided with anode 8, electron emit-
ting electrode 9 and heater electrode 10, is ener-
gized from a source 14 of alternating current 90
supply.

The secondary winding 12 of the transformer
11 is connected to the electrode 10 of the device
7. The primary winding 13 is connected to the
variable resistance 15 and the source of supply 95
14. The variable resistance units 6 and 15 illus-
trated in Figs. 1 and 2 are employed to control
the operation of the electron discharge device
resistors. The variable resistance unit 6 controls
the magnitude of the current flowing through the 100
heater electrode 4 and therefore controls the
electron emission from the electrode 3 since this
emission is proportional to the temperature of
the electrode. The resistance between the elec-
tron emitting electrode and the anode is depend- 105
ent upon the rate of emission from the electron
emitting electrode to a large extent and is there-
fore controlled by the variable resistance unit.
Where alternating current is used to heat the
heater electrode, as is the case when the circuit 110

arrangement illustrated in Fig. 2 is employed, a variable resistance or impedance unit, such as a variable choke coil, may be employed either in the primary or the secondary circuit of the transformer 11 for controlling the current through the heater electrode 10 and the resistance of the electron discharge device 7.

Fig. 3 of the drawings shows a circuit arrangement in which the device 16 is employed to control the anode current flowing from the source 18 through the discharge device 17. Connections are provided between the primary winding of the output transformer 19 and the electron emitting or cathode electrode 16b of device 16.

Connections are also provided between the inductance 20, which is coupled to the inductance 21, and the anode 17a of device 17. A high frequency oscillation by-pass condenser 24 is connected between the inductance 20 and the cathode 17c to provide a relatively low impedance path for high frequency oscillations across the output transformer 19. A variable condenser 22 is connected across the inductance 21. Connections are provided between the grid electrode 17b and the oscillatory circuit comprising condenser 22 and inductance 21. A source of potential 23 is provided to the input circuit of the device 17 for determining the operating characteristics of the electron discharge device 17. The primary winding of the transformer 25 is connected to the source of alternating current supply 26. A variable resistance unit 27 is connected to the heater electrodes 16c and 17d of the electron discharge devices 16 and 17 for varying the current flowing through the circuits of these electrodes from the secondary winding of the transformer 25. Separate variable resistance units may be employed for varying the current through the electrodes 16c and 17d individually. A direct current source of supply may be employed to energize the heater electrodes in place of the alternating current supply. In case a direct current source is employed the transformer 25 is, of course, eliminated. The regenerative condition of the circuit of the electron discharge device 17 is controlled by controlling the anode current flowing from the source 18 through the action of the device 16.

When it is desired to generate high frequency oscillations in the circuits of the device 17 for the purpose of receiving and observing signals of, for example, the continuous wave undamped type, the resistance of the device 16 is reduced to a low value by increasing the current through the electrode 16c so that the electron emission from the electrode 16b increases.

The application of the resistor of this invention to the control of the various circuits of amplifying systems is further illustrated in Fig. 4 of the drawings wherein electron discharge device 28, having anode 28a, cathode 28c and cathode energizing electrode 28b, is employed to control the resistance of the grid circuit of the electron discharge device 29 which is coupled to the circuits of the antenna 33 and the ground 34 through the transformer 35. The anode electrodes 30a and 32a of the devices 30 and 32, respectively, which are similar to device 28, are connected to the source 36 of current supply for controlling the anode current of the discharge devices 29 and 31. Connections are also provided between the cathodes 30c and 32c of the devices 30 and 32, respectively, and the primary winding of transformer 37 and the choke

coil 38 which are connected to the anodes 29a and 31a, respectively. A source 39 of alternating current is connected to the primary winding of the transformer 40 the secondary winding of which is connected to the heater electrodes 28b, 29d, 30b, 31b and 32b of the electron discharge devices 28, 29, 30, 31 and 32, respectively.

Where the source 39 is of approximately the same voltage as that used in the operation of the discharge devices the transformer 40 may be eliminated. Where it is desired, the alternating current source may also be replaced by a direct current source. Variable resistance units 41, 42 and 43 are employed for varying the current through the heater electrodes of the electron discharge devices 28, 30 and 32, respectively, so that the resistance between the electron emitting electrodes and the anodes of these devices may be readily controlled. By varying the value of the resistance unit 41 the resistance of the device 28, which acts as a grid to filament resistor for the device 29, is varied. Likewise by varying the resistance of the resistance units 42 and 43 the anode current of the discharge devices 29 and 31 is varied. Either one of the devices 30 and 32 may be employed as an output control for the amplifying system independently of the other.

Variable resistance units made up of electron discharge devices, such as device 1, may be employed in the anode and grid circuits of transmitters as well as in receiver circuits.

While I have described my invention in several of its embodiments it is to be understood that modifications thereof may be made without departing from the spirit and scope of this invention and that therefore I do not desire to limit this invention to the exact details as set forth in the foregoing specification except as defined by the appended claims.

What I claim as new and desire to secure by Letters Patent of the United States is as follows:

1. In an electrical control system, an electron tube having an anode, a control electrode, a cathode and a cathode heater element; in combination with input and output circuits for said electron tube; means disposed in said output circuit for controlling the resistance thereof, said means comprising a second electron tube having an anode, a cathode connected in said output circuit and a cathode heater element electrically insulated from said cathode; and means for varying the flow of current through the last said heater element whereby the resistance of said second electron tube is varied.

2. In an electrical control system, an electron tube having at least three electrodes, namely, an anode, a control electrode and a cathode; an electron tube having at least two electrodes, namely, an anode and a cathode; cathode heater elements for each of said cathodes, said elements being thermally related to, while electrically insulated from, said cathodes, a source of heating current common to each of said cathode heater elements, an input and an output circuit for the first said electron tube, said output circuit including a space path through the second said electron tube, and means for varying the amplitude of said heating current whereby the resistance of said space path is varied and the potential applied between the cathode and the anode of the first said tube is correspondingly controlled.

LAWRENCE A. HYLAND.
